UNITED STATES PATENT OFFICE

EDWARD V. CULLEN AND ALBERT G. A. SCHMIDT, OF CHICAGO, ILLINOIS, ASSIGNEES
TO CULLEN-FRIESTEDT COMPANY, OF CHICAGO, ILLINOIS, A CORPORATION OF
ILLINOIS

DERRICK

Application filed October 17, 1930. Serial No. 489,310.

The invention relates generally to derricks. More particularly the invention relates to that type of derrick which is designed to travel on a railroad track and to be used in connection with the relaying or repair of the track rails, and comprises (1) a deck which is equipped with a boom and hoisting mechanism, and has mounted thereon an engine for driving the various operating parts of the derrick; (2) a truck which supports the deck rotatably and embodies flanged wheels for sustaining and propelling the derrick on the railroad track; and (3) set-off wheels which are mounted on the truck and operate in conjunction with set-off rails laid transversely across the track to permit the derrick to be shifted laterally and removed from the track rails so as to clear the track for the passage of a train.

One object of the invention is to provide a derrick of this type which embodies power-driven mechanism for driving the set-off wheels so as to expedite and facilitate the work of shifting the derrick laterally from the railroad track.

Another object of the invention is to provide a derrick of the aforementioned character in which the engine on the rotatable deck is used to furnish power for the driving mechanism for the set-off wheels.

A further object of the invention is to provide a derrick of the type hereunder consideration which is generally of new and improved construction and is efficient in operation.

Other objects of the invention and the various advantages and characteristics of the present derrick construction will be apparent from a consideration of the following detailed description.

The invention consists in the several novel features which are hereinafter set forth and are more particularly defined by the claims at the conclusion hereof.

In the drawings which accompany and form a part of this specification or disclosure and in which like numerals of reference denote corresponding parts throughout the several views:

Figure 1 is a plan view illustrating a der-

rick embodying the invention on a railroad track and positioned opposite to a pair of set-off rails:

Figure 2 is a side elevational view exhibiting the manner in which the derrick is tilted vertically so as to permit the hinged sections of the set-off rails to be laid across the railroad track and positioned beneath the set-off wheels;

Figure 3 is a view of the derrick, partly in side elevation and partly in section;

Figure 4 is a plan view of the truck which supports the deck rotatably and embodies flanged wheels for sustaining and propelling the derrick on the railroad track;

Figure 5 is a vertical longitudinal section on the line 5-5 of Figure 4;

Figure 6 is a side view showing the truck supported on the set-off wheels and the construction of the driving mechanism for the set-off wheels; and

Figure 7 is a vertical transverse section of part of the power transmitting mechanism on the rotatable deck.

The derrick which forms the subject matter of the invention is adapted to travel on a railroad track T and is designed to be used in connection with the relaying or repair of the track. It comprises a horizontally rotatable deck 8 and a truck 9. The track T on which the derrick is adapted to travel consists of a pair of rails t which are arranged in parallel relation and are supported on a series of ties t'. The deck 8 is provided at the front end thereof with a pair of brackets 10 and has an internal combustion engine 11 mounted on its rear end. The brackets 10 project upwardly from the deck and form a pivotal support for the inner end of a boom 12. The latter projects forwardly from the front end of the deck and is equipped with hoisting tackle 13 which is operated by the engine 11. The truck 9 on which the deck is supported rotatably comprises a rectangular frame 14, four flanged wheels 15 and four set-off wheels 16. The wheels 15 are adapted to travel on the track rails t and are driven as hereinafter described so as to propel the derrick in either direction along the track T. The set-off wheels 16 extend at right angles

to the wheels 15 and are adapted in conjunction with a pair of set-off rails 17 to permit the derrick to be shifted laterally and removed from the track rails *t* so as to clear 5 the track for the passage of a train. The set-off rails 17 extend transversely to and are positioned above the track rails *t* and are provided with hinged-sections 18 which are adapted to be swung into a position wherein 10 they rest on the track rails and underlie the set-off wheels.

The truck frame 9 consists of longitudinal beams 19 and transverse beams 20. These beams are secured rigidly together and support thereabove a series of floor plates 21. The wheels 15 which are adapted to travel 15 on the track rails *t* are secured together in pairs by means of a pair of axles 22. The latter are mounted in journal boxes 23 which are connected slidably to pedestals 24 and are retained in connected relation with respect to the truck by means of plates 25. The pedestals 24 are connected to and depend from the outermost longitudinal beams 19 20 and have the plates 25 secured to the lower end thereof. Springs 26 are interposed between the journal boxes and the top parts of the pedestals.

The deck 8 is connected rotatably to the 30 frame of the truck by means of a vertically extending sleeve 27 which is provided at the upper end thereof with an annular shoulder 28. The latter abuts against a hub 29 which is located in the center of the deck. The 35 lower end of the sleeve extends through a ring 30 which is secured rigidly to the floor plates 21 and embodies a hub 31. This hub is formed integrally with the ring and is connected by a key 32 to the lower end of the sleeve. A nut 33 on the sleeve abuts against the hub 31 and serves to limit upward movement of the sleeve relatively to the ring. The deck 8 is supported rotatably on the truck frame 9 by means of an annular series 40 of rollers 34. These rollers are mounted on brackets 35 and ride on a track 36 which is formed integrally with the ring 30. Rotation of the deck relatively to the truck is effected by means of a pinion 37 which is 45 mounted on a vertically extending shaft 38 and meshes with a ring gear 39. The latter is formed integrally with the ring 30. The shaft 38 projects upwardly and is driven in any suitable manner by the engine 11 so as 50 to effect rotation of the deck.

The wheels 15 are driven to propel the derrick by mechanism on the deck and the truck. This mechanism comprises a pinion 40 which is keyed or otherwise secured to one end of 55 the crank shaft of the engine 11; an idler gear 41 which meshes with the pinion 40 and is journalled on a stub axle 42; an idler gear 43 which meshes with the gear 42 and is journalled on a stub axle 44; a gear 45 which 60 meshes with the gear 43 and is connected by

a key 46 to one end of a horizontally extending shaft 47; a pair of oppositely facing bevelled gears 48 which are mounted loosely on the central portion of the shaft 47 and mesh with a bevelled gear 49; a vertically extending shaft 50 which extends through the sleeve 27 and has the bevelled gear 49 connected fixedly to the upper end thereof; a low speed bevelled gear 51 which is connected fixedly to the lower end of the shaft 50; a bevelled gear 52 which meshes with the low speed gear 51 and is loosely mounted on a horizontally extending shaft 53; a high speed bevelled gear 54 which is fixedly secured to the shaft 50 above the low speed gear 51; a bevelled gear 55 which meshes with the high speed gear 54 and is mounted loosely on the shaft 53; a pair of bevelled gears 56 which are fixedly secured to a pair of shafts 57 and are driven from the shaft 53 by a pair of intermediate shafts 58; and bevelled gears 59 which mesh with the gears 56 and are fixedly secured to the central portions of the axles 22. The gears 48 and 48^a are connected to rotate with the shaft 47 by means of a clutch collar 60. This collar is slidably mounted on the central portion of the shaft 47 and is connected to rotate with the shaft by means of splines 61. Driving lugs 62 are formed on the ends of the collar and are adapted to interlock with sockets 63 in the hubs of the gears 48 and 48^a so as to effect a driving connection between the collar and said gears. When the clutch collar 60 is shifted in one direction, the gear 48 is locked to the shaft 47 and operates during drive of the shaft to cause rotation of the wheels 15 in one direction. When the clutch collar 60 is shifted in the other direction, the gear 48^a is locked to the shaft 47 and operates during drive of the shaft to rotate the wheels 15 in the opposite direction and effect propulsion of the derrick in a reverse direction. When the clutch collar 60 is in an intermediate or neutral position, neither of the gears 48 and 48^a is locked to the shaft 47 and consequently the derrick remains stationary. Shift of the clutch collar 60 on the shaft 47 is effected by means of a lever 64. This lever is mounted on the deck and is provided with a fork which straddles the collar and embodies inwardly extending pins 64^a. The latter project into an annular groove 65 in the central portion of the clutch collar and operate in response to movement of the lever to shift the collar on the shaft. The collar 60, together with the bevelled gears 48 and 48^a and the various hereinbefore described shafts and gears, exemplifies means whereby the wheels 15 may be driven in one direction or the other from the engine 11 on the rotatable deck. If desired, friction clutches may be used to control the bevelled gears 48 and 48^a instead of the clutch collar 60. The bevelled gears 52 and 55 are connected to rotate the horizontal shaft 53 from 70 75 80 85 90 95 100 105 110 115 120 125 130

the vertical shaft 50 by means of a clutch collar 66. This collar is slidably mounted on the central portion of the shaft 53 and is drivably connected to the shaft by splines 67. Driving lugs 68 are formed on the hubs of the gears 52 and 55 and are adapted to interlock with sockets 69 in the ends of the collar 66 so as to form a driving connection between the gears and the collar. When the collar 66 is shifted into interlocked relation with the gear 52, the gear 52 is locked to the shaft 53 and a low speed drive of the latter is effected through the medium of the low speed bevel gear 58 and the gear 52. When the collar 66 is shifted in the opposite direction, the gear 55 is locked to the shaft 53 and the latter is driven at a high speed through the medium of the high speed bevel gears 54 and the gear 55. The collar 66 and the high and low speed bevelled gears 51 and 54, together with the bevelled gears 52 and 55, exemplify means whereby the shaft 53 may be driven either at a low or high speed from the vertically extending shaft 50. Shift of the clutch collar 66 on the shaft 53 is effected by means of a horizontally extending shaft 70. This shaft is provided at one end thereof with a fork 71. This fork straddles the clutch collar 66 and operates when the shaft 70 is rocked to shift the collar on the shaft 53. The shaft 70 is mounted in a bracket 72 on one of the longitudinal beams 19 and embodies a crank 73 whereby it may be rocked.

The pinion 40 and the gears 41, 43 and 45 are disposed in a housing 74 which is mounted on the rotatable deck 8. The shaft 47 extends horizontally across the central portion of the deck and has the ends thereof journalled in bearings 75 and 76. The low and high speed bevelled gears 51 and 54 and the bevelled gears 52 and 55 are disposed in a housing 77. This housing is located beneath the central portion of the truck frame 14 and is connected in any suitable manner to the two innermost longitudinal beams 19. The shaft 53 extends through the housing 77 and is journalled in bearings 78 which are formed integrally with and project outwardly from the sides of the housing. The intermediate shafts 58 are connected to the shafts 57 and the ends of the shaft 53 by means of universal joints 79 so that the axles 22 are free to move vertically relatively to the truck frame 14. The bevelled gears 56 and 59 which serve to drive the axles 22 from the intermediate shafts 58 are disposed in housings 80. The latter are formed of complementary sections and fit loosely around the axles 22.

The set-off wheels 16 are secured in pairs by means of axles 81. These axles are arranged in parallel relation, extend longitudinally with respect to the truck and are journalled in plates 82 which are connected to and depend from angle brackets 83. The latter, as indicated in Figures 3, 4 and 6 are

connected to the outermost longitudinal beams 19 of the truck frame 14. The set-off wheels 16 are considerably smaller than the wheels 15 and are supported by the axles 81 and the plates 82 so that they are located above the track rails *t* when the truck 9 is supported on the track T by the wheels 15. In removing the derrick from the track by the use of the wheels 16, the deck is first rotated so that it extends lengthwise of the track T. Thereafter, the hoisting tackle 13 is hooked onto one of the track rails *t* and the mechanism for operating the tackle is actuated so as to cause the derrick to tilt vertically as indicated in Figure 2. While the derrick is in its tilted position, the hinged section 18 of the set-off rail that is aligned with the raised end of the truck is swung into its operative position across the track rails *t*. Thereafter, the cable of the hoisting tackle 13 is paid out so as to lower the raised end of the truck and cause the set-off wheels at said truck-end to rest upon the hinged set-off section 18 that extends across the track rails *t*. At the conclusion of these operations, the deck 8 is rotated 180° and the hoisting tackle is again applied to one of the track rails *t* and is operated so as to raise or tilt vertically the other end of the truck. The other hinged section 18 is then swung across the track T. By paying out the cable of the hoisting tackle 13 the raised end of the truck is lowered so as to cause engagement of the set-off wheels at said truck-end to engage the subjacent section 18. The wheels 15 of the truck 9 are elevated with respect to the track T and are positioned so that the flanges thereof clear the track rails *t* and it is thus possible to shift the derrick laterally so as to clear the track T for the passage of a train. The set-off wheels 16 are preferably of the double-flanged type so that they are held against axial displacement with respect to the set-off rails 17.

To facilitate and expedite the work of shifting the derrick laterally, mechanism is provided for driving the set-off wheels 16 from the engine 11 on the rotatable deck 8. This mechanism comprises a gear 84 which is keyed or otherwise fixedly secured to one end of the horizontally extending shaft 53; a gear 85 which is slidably mounted on and is connected by splines to a counter-shaft 86 and is adapted to mesh with and be driven by the gear 84; a sprocket wheel 87 which is fixedly secured to and driven by the counter-shaft 86; and a sprocket wheel 88 which is fixed to one of the axles 81 and is driven from the sprocket wheel 87 by a chain 89. When the gear 85 is shifted into mesh with the gear 84 and the engine 11 on the deck 8 is connected to drive the horizontally extending shaft 53, drive of the set-off wheels is effected through the medium of the counter-shaft 86 and the sprocket wheels 87 and 88.

In view of the fact that the horizontally extending shaft 53 may be driven in one direction or the other in response to manipulation of the clutch collar 60 on the shaft 47, the 5 set-off wheels may be driven in one direction to effect removal of the derrick from the track T and then driven in a reverse direction to shift the derrick back onto the track. By manipulating the clutch collar 66 on the horizontally extending shaft 53, the set-off wheels may be driven at either a high or a low speed. Shift of the gear 85 into mesh with the gear 84 on the horizontally extending shaft 53 is effected by means of a rock 10 shaft 90. This shaft extends transversely with respect to the truck and is provided at one end thereof with a fork 91. The latter straddles the hub of the gear 85 and is connected operatively to the latter by means of a pair of inwardly extending studs or pins 15 92 which project into an annular groove 93. A handle 94 is connected to the other end of the shaft 90 and is located at one side of the truck frame 14 so that it is readily accessible. 20 By manipulating this handle, the shaft may be rocked so as to shift the gear 85 into and out of mesh with the gear 84. The gears 84 and 85 and the sprocket wheels 87 and 88 exemplify simple means whereby the set-off 25 wheels 16 may be driven from the engine on the deck. The shaft 90 is journalled in a pair of brackets 95 which are connected to and depend from two of the longitudinal beams 19. The counter-shaft 86 is journalled at one end 30 thereof in a bearing 96 which is connected to and supported by the housing 77. The other end of the counter-shaft is journalled in a bearing 97 which is connected to a bracket 98. In order to brake the derrick when the 35 latter is shifted onto or off the set-off rails, a brake 99 is provided. This brake comprises a drum 100 and a brake band 101. The drum extends around and is fixedly secured to the hub of one of the gears 48 and 48^a. The 40 band extends around the drum and is adapted to be contracted by any suitable mechanism on the rotatable deck. By virtue of the fact that the gear with which the brake is associated is always in mesh with the gear 49, contraction of the band around the drum will 45 serve to brake the shafts 50 and 53 and stop rotation of the set-off wheels.

The operation of the derrick is as follows:

When the truck 9 is supported on the track 50 and it is desired to move the derrick from one place to another, the clutch collars 60 and 66 are shifted so as to effect drive of the wheels 15 in the desired direction. When the derrick reaches its destination, the operator shifts into neutral position either the clutch collar 60 or the clutch collar 66 so as to disconnect the wheels 15 with respect to the engine 11. When it is desired to remove the derrick from the track so as to clear the track for the passage of a train, the truck 60

9 is moved on the track into a position where-in the wheels 16 are aligned with the set-off rails 17. Thereafter the derrick is manipulated as hereinbefore described so that it is supported by the wheels 16 and the set-off rails 17. To effect lateral shift of the derrick, the clutch collar 60 is shifted by the lever 64 into interlocked relation with one of the gears 48 and 48^a so as to effect a driving connection between the horizontally extending shaft 47 and the vertical shaft 50. The clutch collar 66 is then shifted into interlocked relation with the bevelled gear 52 so as to effect a driving connection between the low speed gear 51 and the horizontally extending shaft 53. Inasmuch as the wheels 15 are supported in an elevated position with respect to the track T, drive of the shaft 53 does not result in the longitudinal displacement of the derrick. When the derrick is in readiness to be shifted laterally from the track T, the operator manipulates the handle 94 so as to rock the shaft 90 and shift the gear 85 into mesh with the gear 84. When the gear 85 is in mesh with the gear 84, the counter-shaft 86 is drivably connected to the shaft 53 and the set-off wheels are driven through the medium of the sprocket wheels 87 and 88. To stop the lateral shift of the derrick, the clutch collar 60 is shifted into its neutral position. When it is desired to return the derrick to the truck, the clutch collar 60 is shifted so as to connect the shaft 50 for reverse drive by the engine 11.

The herein disclosed derrick may be manufactured at a comparatively low cost and is exceedingly efficient in operation. By virtue of the fact that the set-off wheels are power driven, the work of removing the derrick from the track is expedited and facilitated. Since the driving mechanism for the set-off wheels is connected to be driven by the shaft that serves to drive the wheels 15, the construction as a whole is extremely simple.

Whereas a derrick has been described, it is to be understood that the invention may be used equally as well in connection with any type of truck which is adapted to travel on a railroad track and embodies a rotatable deck having an engine mounted thereon. It is also to be understood that the invention is not to be restricted to the details set forth, since these may be modified within the scope of the appended claims, without departing from the spirit and scope of the invention.

Having thus described the invention, what we claim as new and desire to secure by Letters Patent, is:

1. In combination, an elongated truck having a flooring on the top thereof and provided with a pair of wheels at each end thereof for travel on a railroad track, a motor associated with the truck, mechanism for propelling the truck along the track comprising a longitudinally extending shaft under the truck-floor- 125

ing connected to be driven by the motor and geared to the wheels, transversely extending set-off wheels mounted between the pairs of wheels at the ends of the truck and under the truck-flooring to rotate on fixed axes and adapted in response to tilting of the truck to be placed upon set-off rails laid across the track and in conjunction with the set-off rails to support the truck in an elevated position with respect to the track to permit it to be shifted laterally, mechanism for driving the set-off wheels for truck-shifting purposes comprising gearing between the longitudinally extending shaft and certain of the set-off wheels, and means including a control lever at one side of the truck whereby said gearing may be disconnected from drive by the shaft in order to permit of stoppage of the truck during lateral shift thereof and of discontinuance of drive of the set-off wheels during propulsion of the truck on the track.

2. In combination, an elongated truck having a pair of wheels at each end thereof for travel on a railroad track and embodying a pair of laterally spaced, longitudinally extending side beams, a motor associated with the truck, mechanism for propelling the truck comprising a longitudinally extending shaft under the truck connected to be driven by the motor and geared to the wheels, a pair of longitudinally extending axles positioned directly under the side beams of the truck and on opposite sides of the longitudinally extending shaft of the propelling mechanism, four set-off wheels mounted on the ends of the axles respectively and adapted to be placed upon set-off rails laid across the track and in conjunction with the set-off rails to support the truck in an elevated position with respect to the track to permit it to be shifted laterally, and mechanism for driving the set-off wheels for truck-shifting purposes including a chain and sprocket connection between the shaft of the propelling means and one of the axles for the set-off wheels.

3. In combination, an elongated truck having a flooring on the top thereof and provided with a pair of wheels at each end thereof for travel on a railroad track, a motor associated with the truck, mechanism for propelling the truck comprising a longitudinally extending shaft under the truck-flooring connected to be driven by the motor and geared to the wheels, a pair of longitudinally extending axles positioned under the sides of the truck and on opposite sides of the longitudinally extending shaft of the propelling mechanism, four set-off wheels mounted on the ends of the axles respectively and adapted to be placed upon set-off rails laid across the track and in conjunction with the set-off rails to support the truck in an elevated position with respect to the track to permit it to be shifted laterally, mechanism for driving the set-off wheels for truck-shifting purposes including

a chain and sprocket connection between said shaft of the propelling means and one of the axles for the set-off wheels, and means including a lever at one side of the truck whereby the chain and sprocket connection may be disconnected from drive by the longitudinal shaft in order to permit of stoppage of the truck during lateral shift thereof and of discontinuance of drive of the set-off wheels during propulsion of the truck on the track.

4. In combination, a truck having wheels adapted to travel on a railroad track, a motor associated with the truck, mechanism for propelling the truck in either direction on the track comprising clutch-controlled reversible gearing between the motor and the wheels, transversely extending set-off wheels mounted on the under side of the truck to rotate on fixed axes and adapted in response to tilting of the truck to be placed upon set-off rails laid across the track and in conjunction with the set-off rails to support the truck in an elevated position with respect to the track to permit it to be shifted laterally, and mechanism for driving the set-off wheels consisting of gearing driven by the gearing of the truck-propelling means and operative to drive the set-off wheels in one direction when the truck-propelling gearing is set for normal drive, and to drive the set-off wheels in the reverse direction when the truck propelling gearing is set for reverse drive.

5. In combination, an elongated truck having wheels at the ends thereof adapted to travel on a railroad track, a motor associated with the truck, transversely extending set-off wheels mounted on the under side of the truck to rotate on fixed axes and adapted in response to tilting of the truck to be placed upon set-off rails laid across the track and in conjunction with the set-off rails to support the truck in an elevated position with respect to the track to permit it to be shifted laterally, and clutch-controlled, reversible gearing driven by the motor and operative to drive the set-off wheels in either direction for truck-shifting purposes.

6. In combination, a truck having wheels adapted to travel on a railroad track, a deck mounted rotatably on the truck, power-means on the deck, a vertical shaft connected to be driven by the power-means and concentric with the axis about which the deck is rotatable, set-off wheels mounted on the under-side of the truck so that they are adapted in conjunction with set-off rails laid across the track to support the truck in an elevated position with respect to the track and permit it to be shifted laterally, and mechanism for driving the set-off wheels for truck shifting purposes mounted on and supported by the truck and connected to be driven from the aforesaid shaft.

7. In combination, a truck having wheels

- adapted to travel on a railroad track, a deck mounted rotatably on the truck, power-means on the deck, a vertical shaft connected to be driven by the power-means and concentric with the axis about which the deck rotates, set-off wheels mounted on the under-side of the truck so that they are adapted in conjunction with set-off rails laid across the track to support the truck in an elevated position with respect to the track and permit it to be shifted laterally, and reversible gearing for driving the wheels in one direction or the other for truck shifting purposes mounted on and supported by the truck and driven by the aforesaid vertical shaft. 70
- 8: In combination, a truck having wheels adapted to travel on a railroad track, a deck mounted rotatably on the truck, power-means on the deck, a vertical shaft connected to be driven by the power-means and concentric with the axis about which the deck rotates, mechanism for driving the wheels to propel the truck on the track mounted on and carried by the truck and driven by the shaft, set-off wheels mounted on the under-side of the truck so that they are adapted in conjunction with set-off rails laid across the track to support the truck in an elevated position with respect to the track and permit it to be shifted laterally, and mechanism for driving the set-off wheels for truck shifting purposes mounted on and carried by the truck driven by the first mentioned mechanism and including a clutch whereby drive of the set-off wheels may be discontinued during propulsion of the truck on the track by the truck wheels. 75
- 9: In combination, a truck having wheels adapted to travel on a railroad track, a deck mounted rotatably on the truck, an engine on the deck, a vertical shaft connected to be driven by the motor and concentric with the axis about which the deck is rotatable, reversible gearing on the truck driven by the vertical shaft and connected by a horizontal shaft to drive the wheels in one direction or the other, set-off wheels mounted on the under-side of the truck so that they are adapted in conjunction with set-off rails laid across the track to support the truck in an elevated position with respect to the track and permit it to be shifted laterally, and mechanism for driving the set-off wheels for truck shifting purposes driven by the horizontal shaft and including a clutch whereby drive of the set-off wheels may be discontinued during propulsion of the truck on the track by the truck wheels. 80
- 10: In combination, a truck having wheels adapted to travel on a railroad track, a deck mounted rotatably on the truck, power-means on the deck, set-off wheels mounted on the truck and adapted in conjunction with set-off rails laid across the track to support the truck in an elevated position with respect to the track and permit it to be shifted laterally, clutch-controlled mechanism for driving the set-off wheels from the power-means, and means controlled from the deck for braking the set-off wheels. 85
- 11: In combination, a truck having wheels adapted to travel on a railroad track, a deck mounted rotatably on the truck, power-means to propel the truck on the track, set-off wheels mounted on the truck and adapted in conjunction with set-off rails laid across the track to support the truck in an elevated position with respect to the track and permit it to be shifted laterally, and means controlled from the deck for braking the set-off wheels. 90
- Signed at Chicago, Illinois, this 1st day of October, 1930.
